(57) **CLAIM**

I claim the ornamental design for a combination electrical cabinet and sign, as shown and described.

DESCRIPTION

FIG. 1 is a front right-side perspective view of a combination electrical cabinet and sign shown in a closed position; FIG. 2 is a front right-side perspective view of the combination electrical cabinet and sign shown in an open position; FIG. 3 is a top perspective view of FIG. 1;

FIG. 4 is a bottom plan view thereof;

FIG. 5 is a front elevation view thereof;

FIG. 6 is a rear elevation view thereof;

FIG. 7 is a right elevation view thereof;

FIG. 8 is a left elevation view thereof;

FIG. 9 is a front elevation view of a combination electrical cabinet and sign shown in an environment of use; and, FIG. 10 is a top perspective view of a combination electrical cabinet and sign with the four corner caps removed for clarity of illustration.

The broken lines in FIGS. 1-3 and 5-9 depict environmental structures that form no part of the claimed design.
